UNITED STATES PATENT OFFICE.

CHARLES I. HALL, OF MOUNT VERNON, WASHINGTON.

AUTOMATIC CROSSING-GATE.

1,143,190.

Specification of Letters Patent. Patented June 15, 1915.

Application filed May 24, 1913. Serial No. 769,678.

To all whom it may concern:

Be it known that I, CHARLES I. HALL, a citizen of the United States, residing at Mount Vernon, in the county of Skagit and State of Washington, have invented certain new and useful Improvements in Automatic Crossing-Gates, of which the following is a specification.

This invention relates to new and novel gates, and more particularly, to improvements in automatic gates which are used at the crossings of highways and railways for the prevention of accidents.

The primary object of this invention is the provision of gates of this nature which are automatically operated, through the medium of electrical means, by a train or car upon the railway, approaching the highway, thus forming a closure for the crossing 20 of the two ways and preventing any vehicle, or the like, from entering upon the railway.

A still further object of this invention is to simplify and improve the construction of devices of this nature as is consistent with the performing of its fundamental functions, and a device with which the gates may be held closed for any length of time during the passing of a car or train upon 30 the track.

With the foregoing and other objects in view, this invention consists in such novel features of construction, combination and arrangement of parts as will be hereinafter 35 more fully described, illustrated in the accompanying drawings and claimed.

In describing the invention in detail, reference will be had to the accompanying drawings wherein like characters of reference 40 designate like or corresponding parts throughout the several views, and in which,

Figure 1 is a side elevation of the improved gate and operating mechanism therefor showing the gates in an open or raised 45 position: Fig. 2 is a view similar to Fig. 1, only showing the gates lowered and forming a closure for the crossing of the highway and railway: Fig. 3 is a top plan view of the improved gates showing the same in 50 position beside a railway; and Fig. 4 is a diagrammatical view of the electrical operating arrangement.

Referring to the drawings by numeral, 1 designates a railway which is constructed in the usual manner of T-rails 2 and cross 55 ties 3, and which has arranged along side thereof the platform 4.

The platform 4 forms a covering for a cavity or pit 5, which is cut or formed within the ground directly under the highway 60 (not shown), and adjacent to the railway as is clearly shown in Fig. 3 of the drawings. Mounted upon the platform 4 are crossing gates 5 which are composed, each gate, of bars 6 and 7, which are pivotally mounted 65 upon standards 8 and 9. The standards 8 and 9 are mounted upon the platform 4 by any suitable means such as bolts 10, so that they will not interfere with the traveling 70 of a vehicle, or the like, upon the highway.

The bars 6 and 7 are of the construction which is usually employed in gateways of this type, and are pivoted in the usual manner on the standards 8 and 9. The bars 6 and 7, which form the gate have a rope 10 75 connected thereto, one end of the rope connected by each of the bars as is shown at 11. The rope 10 after passing for a short distance along the upper edge of the bars 6 and 7 is curved about the ends thereof, extends 80 downwardly through openings 12 in the platform 4, and about a pulley 13 which is mounted in a pulley-guard 14.

The pulley-guard 14 has rings 15 and 16 connected to its upper and lower ends respectively, and the weight 17 is connected to the ring 16 in any suitable manner. The weight 17 is of a size so that when the gate-bars 6 and 7 are not forcibly held under tension, the weight will counterbalance and 90 cause them to stand upright, or opened, as is shown in Fig. 1 of the drawings.

A rope 20 is secured to the ring 15 in any suitable manner, passes about a pulley 21, and is connected to a drum 22. The pulley 95 21 is mounted in a bracket 23, which is secured in any manner to the inner surface of the platform 4.

The drum 22 is rigidly mounted upon the shaft 24 of motor 25, which motor 25 is 100 mounted upon a platform 26 placed in one side of the pit 5, as is clearly shown in both Figs. 1 and 2 of the drawings. The motor 25 is connected to the series of batteries 27

or other electrical energy generating system by an electrical conducting wire 28. The batteries 27 are also mounted in any convenient position within the pit 5, and have 5 an electrical conducting wire 29 connected to one of the series of the batteries and to one of the T-rails 2 of the railway 1. Another electrical conducting wire 30 is connected to the motor 25, and to the other of 10 the T-rails of the railway 1. This connecting of the wires is clearly set forth in the diagrammatical view shown in the drawings. The electrical conducting wires are connected to the various parts as heretofore 15 described, so that when the circuit is closed between the two rails of the railway 1, electrical energy will be imparted to the motor 25. The wire 30 is protected from engagement with foreign articles, and also atmospheric effects by a metallic or other suitable 20 tubing 31.

From the foregoing description and the drawings, it will be seen that when a locomotive, or similar device, approaches the 25 gates which are mounted, as has been heretofore described, the wheel axles of the locomotive will close the circuit between the two rails of the track 1, and circuit between the two poles of the batteries 27. This closing 30 of the circuit between the opposite poles of the batteries 27 will cause the motor 25 to rotate, owing to the imparting of electrical energy thereto. The rotating of the motor 25 will also rotate the shaft 24, and the drum 35 22 which is rigidly mounted thereupon. As the rope 20 is securely connected to the drum 22, it will, upon the rotation of the drum, be wound to the drum, and this winding of the rope 20 to the drum will forcibly raise the 40 weight 17 to a position as is shown in Fig. 2 of the drawings, thus allowing the bars 6 and 7 of the gate 5 to lower and form a closure for the crossing of the highway and the railway, as is shown in Fig. 2. The weight 45 will be held in a raised position until it is desired to have the gates returned to their raised position since the pull by the motor upon the line 20 continues until the train or car has passed the crossing and the circuit 50 through the motor is again broken. Immediately after the train leaves the portion of the track 1, which is connected to the wires 29 and 30, the circuit between the opposite poles of the series of batteries 27 will be 55 broken and the rotation of the motor, due to electrical energy, will cease, thus relieving the weight 17 of the tension thereupon. This latter feature will allow the weight 17 to drop downwardly and assume position as is 60 shown in Fig. 1 of the drawings, forcing bars 6 and 7 in an upright position.

The time when the gates are lowered, during the passing of the locomotive or the like, over the tracks, depends entirely upon the

length of track, or T-rails, which are connected in conductive relation to the batteries 27.

In practical fields, certain minor features of construction, combination, and arrangement of parts may necessitate alterations to 70 which the patentee is entitled, provided such alterations are comprehended within the scope of what is claimed.

What is claimed is:

1. In a railway crossing gate the combination, 75 of gate-bars pivotally mounted upon standards, a rope connected to said gate-bars, said rope passing about a pulley, a pulley guard about said pulley, a weight secured to said pulley-guard, said weight adapted to normally hold said gate-bars in an upright position, and train controlled means connected to the upper portion of said pulley-guard for raising said weight to permit said gate-bars to lower, and assume a 80 horizontal position when a train or the like is passing.

2. In a railway crossing gate the combination of a platform, standards carried by 90 said platform, gate-bars pivotally connected with said standards, a cable having its end portions secured to said gate-bars and passing beneath said platform, a pulley guard straddling said cable beneath said platform and provided with a pulley wheel resting 95 upon said cable, a weight carried by said pulley guard, a guide carried by said platform above said pulley guard, a drum, a line wound upon said drum and passing through said guide and connected with said pulley 100 guard, and train controlled electrically operated means for rotating said drum to wind the line thereon and raise said weight to permit said gate-bars to move to a lowered 105 position.

3. In a railway crossing gate the combination, 110 of gate-bars pivotally mounted upon standards, a rope connected to said gate-bars, said rope passing about a pulley, a pulley-guard about said pulley, a weight secured to said pulley-guard, said weight adapted to normally hold said gate-bars in an upright position, and train controlled 115 electrically operated means connected to the upper portion of said pulley-guard for raising said weight and permitting said gate-bars to lower or assume a horizontal position when a train or the like is passing.

4. In a railway crossing gate the combination, 120 of gate-bars pivotally mounted upon standards, a rope connected to said gate-bars, said rope passing about a pulley, a pulley-guard about said pulley, a weight secured to said pulley-guard said weight adapted to normally hold said gate-bars in an upright position, said weight and said rope mounted within a pit beneath said gate-bars, a plurality of electrical batteries with- 125

in said pit, electrical conductors connecting one of the poles of said batteries to the rails of the railways, electrical conductors connecting the other pole of said batteries to an electrical motor, means carried by said electrical motor and connected to said pulley-guard for causing the said gate-bars to assume a horizontal position when the circuit

is closed between the two poles of the series of batteries.

In testimony whereof I affix my signature in presence of two witnesses.

CHARLES I. HALL.
